UNITED STATES PATENT OFFICE.

WILLIAM C. WHITE, OF SCHENECTADY, NEW YORK, ASSIGNOR TO GENERAL ELECTRIC COMPANY, A CORPORATION OF NEW YORK.

ELECTRON-DISCHARGE APPARATUS.

Application filed June 5, 1922. Serial No. 586,024.

My present invention relates to electron discharge devices and means for supporting such devices and supplying current thereto.

One of the objects of my invention is to provide a simple construction for electron discharge devices, particularly of the three-electrode type, and a mounting for such devices which will hold them securely in the desired operating position and serve to provide electrical connections for supplying current for their operation.

In the operation of electron discharge devices of the type here involved, particularly for the amplification of high frequency currents, difficulty is experienced because of the capacity which is present between the grid and anode electrodes. By reason of this capacity the efficiency of such devices for amplifying purposes when employed in the usual manner is greatly reduced. A further object of my invention is to provide a construction which will reduce to a minimum the capacity between these two elements, thereby permitting their operation at a higher efficiency than has heretofore been possible.

It has been customary in the past to bring all of the leading-in conductors which supply current to the electrodes out at one end 30 of the receptacle in which the electrodes are enclosed and to provide a base for the receptacle consisting of a metal shell which encloses a disc of insulating material in which the contacts through which current is supplied to the device are mounted. The addition of this base to the device results in an appreciable increase in the capacity between anode and grid electrodes, which is objectionable for the reason above set forth.

In carrying my invention into effect I eliminate this objectionable feature in the present form of the three-electrode electron discharge device. This is accomplished by extending the leading-in conductors which supply current to the electrodes only a short distance outside of the tube and arranging them in such a way that the ends of the leading-in conductors are adapted to 50 make direct contact with contact members through which current may be supplied. I also bring the leading-in conductor which supplies current to the anode out of one end of the tube and the leading-in conductors which supplies cur-

rent to the grid out of the opposite end of the tube. As a result the capacity between these leading-in conductors which is present in the usual tube construction is almost completely eliminated, the only capacity between the two electrodes being the unavoidable capacity present by reason of their parallel relation. By cutting off the leading-in conductors so that they extend only a short distance outside the tube the portions extending out of the tube will be rigid enough to serve also as supports for the tube and it will be possible to securely support the tubes from suitable contacts so positioned as to make contact with the leading-in conductors extending from the opposite ends of the tube.

The novel features which I believe to be characteristic of my invention are set forth in the appended claim, the invention itself however both as to its organization and method of operation will best be understood by reference to the following description taken in connection with the accompanying drawing in which Fig. 1 is a perspective view of an electron discharge device constructed in accordance with my invention and mounted in a suitable holder, and Fig. 2 is a plan view of the same with a portion of the holder cut away.

As indicated in the drawing the electron discharge device comprises a tubular receptacle 1 containing a cylindrical anode 2 and grid and filament or cathode electrodes within this anode. The filament, which is not shown, is supported from its opposite ends by the supporting members 3 and 4. A leading-in conductor 5 is connected to the supporting member 3 through a spring 6, which provides the desired tension on the filament, and leading-in conductor 7 is connected to supporting member 4 through a transverse arm 8. A leading-in conductor 9 supplies current to the grid, which is not shown, but which is supported on a rod 10. The anode 2 is supported from its two ends by the arms 11 and 12. The arm 11 is attached to the transverse arm 8 but insulated therefrom by means of a bead 13 of insulating material and arm 12 is attached to a bridge 14 of insulating material through which the leading-in conductors 5, 7 and 9 pass.

By this construction it is possible to assemble the three electrodes of the device in

their desired spaced relation before they are sealed into the tube. Current is supplied to the anode by means of a leading-in conductor 15, which is connected to the arm 11 5 through a flexible connection 16. The leading-in conductors 5, 7, 9 and 15 are made to extend only a short distance outside of the receptacle 1. In this way even though the leading-in conductors are comparatively 10 flexible, the portion extending outside of the receptacle 1 will be sufficiently rigid to securely support the device.

I have shown in the drawing as a supporting means for the device described a 15 base 17 having mounted thereon two flexible contact members 18 and 19 positioned just far enough apart so that when the receptacle 1 is placed between them the leading-in conductors 9 and 15 will make contact 20 with both of these spring members. An upright support member 20, which is mounted on the base 17 carries the two spring contact members 21 and 22, which are preferably in the same plane as contact 25 member 19, and these contact members 21 and 22 are arranged so as to make contact with the ends of the leading-in conductors 5 and 7 through which current is supplied to the filament. The upright member 20 is 30 provided with an opening 23, which serves as a guide for the insertion of one end of the device into the holder. The guide member 24 is also provided for convenience in 35 guiding the opposite end of the device so that the leading-in conductor 15 will make contact with the contact member 18. The

contact members 18, 19, 20, 21 and 22 are provided with suitable binding posts 25 for connecting the device in the circuit in which it is to be employed.

While I have shown and described the preferred embodiment of my invention it will be apparent that my invention is by no means limited to the particular embodiment shown and described but that many 45 modifications in the form and arrangement of the electrodes of the electron discharge device, as well as in the manner in which the contact members are arranged, may be made without departing from the scope of 50 my invention as set forth in the appended claim.

What I claim as new and desire to secure by Letters Patent of the United States, is:—

An electron discharge device having 55 cathode, grid and anode electrodes, leading-in conductors for said cathode and grid electrodes extending from one end of said device, a leading-in conductor for said anode extending from the opposite end of said device and a plurality of spring contact members extending into one plane adapted to make contact with the ends of the leading-in conductors for the grid and cathode leading-in conductors, and a single contact 60 member extending in a parallel plane and adapted to make contact with the end of the leading-in conductor for the anode.

In witness whereof, I have hereunto set my hand this second day of June, 1922.

WILLIAM C. WHITE.
